Inventor,
William H. Byrd.
Attorney.

UNITED STATES PATENT OFFICE.

WILLIMAN HARVEY BYRD, OF SOUR LAKE, TEXAS.

FIRE-EXTINGUISHING DEVICE.

1,346,099.

Specification of Letters Patent.

Patented July 6, 1920.

Application filed January 6, 1920. Serial No. 349,720.

To all whom it may concern:

Be it known that I, WILLIMAN H. BYRD, a citizen of the United States of America, and resident of Sour Lake, in the county of Hardin and State of Texas, have invented certain new and useful Improvements in Fire-Extinguishing Devices, of which the following is a specification.

This invention relates to fire extinguishing devices and is designed primarily for use as associated with containers for combustible fluids such as oil and the like, and the said invention has for its object the provision of novel means for supplying steam to the fluid so that oxygen sufficient to support combustion will not reach the flame, the said invention having for its object furthermore the provision of novel means for installing the apparatus in a receptacle or tank and providing means whereby the steam may be delivered to the fluid in the tank so that the steam will pass through the fluid whereas other steam will be forced downwardly on the flame and on to the surface of the burning fluid.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a plan view of the apparatus embodying the invention, the receptacle being shown in section; and

Fig. 2 illustrates a vertical sectional view of a receptacle with the device applied thereto.

In these drawings 5 denotes a receptacle such as a tank of the storage type for holding oil and 6 denotes a curved piping which surrounds the tank at the bottom. The pipe 6 might be termed a header in that it has a steam supply pipe 7 leading to it from any suitable source.

At a predetermined location and preferably at each 90° of the circle risers 8 are tapped into the header and these risers extend to nearly the top of the tank. The upper ends of the risers have couplings 9 of appropriate type to which horizontally disposed joints 10 are connected, the said joints

being in communication with a sprinkler or spraying ring 11 supported within the tank by the brackets 12. The sprinkler ring 11 is formed in sections and each section has its ends joined to four-way couplings 13, it being understood that the joints 10 lead into one branch of each of said couplings. Horizontally disposed sprinkler pipes 14 are connected to other branches of the couplings and the said pipes 14 are connected to branches 15 of a spider 16 which occupies the center of the tank near the top, the said spider having a downwardly extending sprinkler pipe 17 connected to it, the said pipe 17 terminating near the bottom of the tank and having radial sprinkler branches 18 which rest on the bottom of the tank to aid in supporting the structure and for the delivery of steam at the bottom of the tank.

Each coupling 9 has a valve stem 19 rising from the valve plug 20 rotatable in the coupling and by this means, the circulation of steam may be controlled although in most instances it will not be necessary to interpose a valve in the coupling 9 for the reason that each riser has a valve 21 near the bottom which may be manually operated to permit the circulation of fluid.

The arms of the spider have the pipes 14 connected to them by means of the threaded couplings 22 and the joints 10 may comprise a nipple 10^a threaded in the coupling 10^b which coupling 10^b is in communication with the four way coupling 13 but these latter features are details of construction which may be varied to suit particular requirements although the device as shown embodies the preferred construction as far as it has been developed.

The apertures of the ring and sprinkler tubes at the top of the tank should open downwardly or those in the ring might open diagonally inwardly, and the sizes of these apertures and their exact location may be varied to suit particular requirements and the same is true with respect to the proportions or sizes of the ring pipes, risers and the other tubing and connections as much will depend upon the size of the tank, the pressure of steam available and the like.

I claim—

1. In a fire extinguishing apparatus, a tubular ring at the bottom of the tank exteriorly thereof, risers extending therefrom, radially extending pipes connected to the risers and extending crosswise of the tank,

near the top, a hollow spider to which the pipes are connected, the said pipes having perforations therein, a sprinkler ring connected to the pipes within the tank, a vertically disposed perforated pipe connected to the center of the spider and radiating sprinkler pipes connected to the bottom of the vertically disposed perforated pipe.

2. In a fire extinguishing apparatus, a 5 sprinkler ring within a tank, means for supporting the ring therein, means for supply-

ing the ring with steam, radially extending pipes extending inwardly from the ring and connected thereto, a spider having hollow arms to which the radially disposed pipes are connected, a vertically disposed perforated pipe connected to the spider, and radially disposed sprinkler arms at the bottom of the tank connected to the said vertically disposed perforated pipe. 15

WILLIAM HARVEY BYRD.
